CLAIM

The ornamental design for a case for fishing rods, as shown.

DESCRIPTION

FIG. 1 is a right side elevational view of a case for fishing rods, showing my new design;

FIG. 2 is a top plan view thereof;

FIG. 3 is a bottom plan view thereof;

FIG. 4 is a front end elevational view thereof;

FIG. 5 is a rear end elevational view thereof;

FIG. 6 is a left side elevational view thereof in the open position; and

FIG. 7 is a perspective view thereof.
